(57) **CLAIM**

The ornamental design for a tire, as shown and described.

DESCRIPTION

FIG. 1 is a perspective view of a tire of the present application;

FIG. 2 is a side view of the tire;

FIG. 3 is an enlarged, partial side view;

FIG. 4 is a front view of the tire; and,

FIG. 5 is an enlarged partial front view thereof.

The broken line showings of the inner bead, and sidewall extending to the solid line boundary between the tire and the sidewall, are included for the purpose of illustrating environment and form no part of the claim.
